CONTROL CIRCUIT

Hubert H. Wittenberg, Lancaster, Pa., assignor
to Radio Corporation of America, a corporation
of Delaware

Application October 6, 1947, Serial No. 778,217

9 Claims. (Cl. 315—262)

1

My invention relates to electric discharge apparatus and more particularly to control or excitation circuits utilizing electric discharge means.

In some industrial applications, as for example in electric resistance spot welding systems, it is desirable to employ control circuits which accurately determine the time interval of current flow.

It is an object of my invention to provide an improved control system supplying a current pulse of predetermined duration to a load.

A further object of my invention is to provide a control system whereby the current pulse interval can be accurately controlled.

An ancillary object of my invention is to provide a control means, simple in design, wherein the occurrence of such a current pulse is controllable by means of a switch or pushbutton device.

According to my invention, I provide a control system of simple structure for the main discharge apparatus through which current is supplied intermittently to a load. The system incorporates a gaseous discharge device normally maintained inoperative, an auxiliary electric discharge device, a circuit to provide an energizing pulse in predetermined phase relation to the anode potential of the main discharge device, and a capacitor which is charged by the current pulse of the current through the auxiliary discharge device. The current pulse is conducted through the control electrode of the main discharge device causing conduction thereof. Charging of the capacitor prevents but a single pulse through the main discharge device.

The organization and method of operation, together with additional objects and advantages thereof will be apparent from the following description when read in connection with the accompanying drawing, in which the single figure shows schematically a specific embodiment of my invention.

Referring to the drawing, the apparatus shown comprises a welding transformer 1, across the secondary of which a pair of welding electrodes 2 are connected. The electrodes engage the material to be welded and when the transformer 1 is energized, welding current flows through the electrodes and the material. The primary winding 3 of the transformer 1 is supplied with power from the line conductors 4 and 5 in series with the main discharge device 6 which is preferably of the immersed-ignition electrode type. The main discharge device comprises an anode 7, a mercury pool cathode 8, and an ignition electrode 9, immersed in the mercury pool. Arc discharges are initiated between the anode 7 and cathode 8 by transmitting to the control member 9 a current of sufficient magnitude to initiate a cathode spot. In the chosen embodiment, this ignition current is supplied through an auxiliary discharge device 10 of the gaseous discharge type, having an anode

2

11, a control electrode 12, and a heater type cathode 14. Heater voltage for its cathode is supplied by a transformer 15, the primary 16 of which is connected across the line conductors 4 and 5 in series with a resistor 18. The auxiliary discharge device, in combination with an inductance 19, a capacitor 20, the ignitor electrode 9, and the cathode 8, of the main discharge device, are in series with the line conductors 5 and 17. The inductance 19 is utilized to reduce the rate of rise of current, thus prolonging the life of the auxiliary discharge device.

In parallel with the capacitor 20 is a series network comprising a resistor 21 and contact points 23 and 24 of a push-button switch 22. The control electrode 12 of the auxiliary discharge device is connected to its cathode 14 through a capacitor 25 which is adapted to stabilize the auxiliary discharge device against line surges and extraneous pickup. The control electrode 12 is also connected through a grid leak resistor 26 in parallel with a capacitor 27 to a contact point 28 of the switch 22. Bias voltage for the auxiliary discharge device is composed of the heater voltage 180° out of phase from the anode voltage, and a direct current component generated in the combination of the resistor 27 and the condenser 28. The contact point 28 is returned to the cathode 14 and one side of the secondary winding 29 of transformer 15 through a resistor 30. The side of the latter resistor, which is connected to the secondary winding 29 is also connected to the anode of a discharge device 31 as well as to one side of a load resistor 32 and a resistor 33. The other side of the resistor 33 is connected to a contact 37 of the switch 22. Discharge device 31 comprises an anode 34, a control electrode 49, and a hot cathode 36. The other side of the load resistor 32 is connected to the contact 37 of the switch 22 through a capacitor 38. This capacitor along with the resistor 33 forms a voltage divider network across the load resistor 32. There is also provided a transformer 39 having a primary winding 40, a secondary winding 41, and a tertiary winding 42. Primary potential is supplied by the voltage drop across the resistor 18. The tertiary winding 43 serves to provide heater voltage for the cathode 36 of the discharge device 31. A phase shifting circuit, composed of a variable resistor 43 and a fixed capacitor 44, connected in series, is connected across the secondary winding 41. The anode 34 of discharge device 31 is connected through the load resistor 32 to the common contact 46 of the capacitor 44 and the resistor 43 which is the source of potential for said anode. The cathode 36 of the discharge device 31 is connected to the center tap 45 of the transforming winding 41; this center tap serves to provide a reference potential for the discharge device 31 and its associated circuit.

Between the points 45 and 46 is connected a phase shift network composed of a resistor 47 and a capacitor 48. The potential developed across the capacitor 48 is used to supply excitation voltage to the control electrode 49 of the discharge device 31.

The theory of the operation of my device may best be understood by considering the well known fact that in a circuit containing resistance and capacitance the phase of the potential developed across the capacitance will lag the phase potential developed across the resistance by approximately ninety degrees. The instantaneous relative magnitude of the potentials is dependent upon the relative value of impedance of the components. Resistor 43 and capacitor 44 in combination with the center-tapped winding 41 constitute a phase shift network which will provide an output voltage between the points 45 and 46 which is constant in magnitude but variable in phase (by means of the variable resistor 43) over nearly 180° .

It is to be understood that the capacitor 44 can be made adjustable, and that such an adjustment would enable a greater phase shift.

It will be seen that the total potential difference of secondary winding 41 is applied across this resistance capacity series combination, whereas the source of potential for the anode 34 of the discharge device 31 is the common connection of the resistor 43 and the capacitor 44.

The relative magnitude of these potentials may be varied by adjusting the relative values of said capacitor and resistor, which are variable. Due to the quadrature phase relation of the potential difference across the capacitor and the potential difference across the resistor the resultant potential difference between points 45 and 46 is adjustable in phase relation with the potential across secondary winding 41. It will be clear that this is also a phase adjustment with respect to the supply potential.

Again, it is known that in order to effect conduction of a gaseous discharge device, it is necessary to apply a positive potential to the control electrode circuit of the electric discharge device during the interval in which the anode potential of the electric discharge device is positive, this phase relation of applied electrode potential will be referred to as a favorable phase relation.

It will be seen that when the common connection of the resistor and capacitor is positive with respect to the center tap a positive potential will be applied through the anode load circuit of the discharge device 31 to the anode 34 and, at the same time, a sinusoidal voltage lagging the anode voltage by 90° , will be developed across the capacitor 48. This voltage is applied to the control electrode 49 of the discharge device 31, rendering it conductive. Conduction of the discharge device persists for the remainder of the cycle, or 90° . Rapid ionization of the discharge device 31, which is of the gaseous type, causes a pulse similar to that obtained from a peaking transformer thus causing a steep positive wave-front to be developed across the anode load resistor 32. The capacitor 38 and the resistor 33 differentiate the voltage across the resistor 32 so that a pulse appears across the resistor 33. This excitation pulse occurs at the same frequency as that of the supply potential.

When a welding pulse is desired switch 22 is depressed causing electrical contact between switch contact points 37 and 28 and, hence, the

application of a pulse of positive potential to the control electrode 12 of the auxiliary discharge device 10. This pulse is of sufficient magnitude to overcome the bias which is normally negative, on the control electrode, and is adjustable, by the means described above, in phase relation with the anode 11, cathode 14, potential so as to cause the auxiliary discharge device to strike in any desired time relation to the said impressed anode-cathode potential. Conduction by the auxiliary discharge device causes current to be drawn through the mercury pool cathode 8 and ignitor electrode 9 of the main discharge device, causing said device to be rendered conductive in view of the fact that said current is in favorable phase relation to impressed potential of the main discharge device.

The main discharge device 6 will remain conductive during the remaining portion of the half cycle of anode cathode voltage; but by reason of the alternating nature of the supply potential conduction by the main discharge device will cease when the potential falls below that required to maintain ionization. The pulse of current through the main discharge device is drawn through the primary 3 of welding transformer 1 and by transformer action a potential and consequently a welding current is produced in the secondary winding 2. Only a single pulse occurs because the ignition pulse through auxiliary discharge device 10 charges condenser 20 to line potential preventing further current flow until switch 22 is released causing electrical contact between contact points 22 and 23 and allowing condenser 20 to discharge through resistor 21. The charging time of said condenser is small with respect to the period of the supply potential.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. In a control system, a source of alternating potential, a load, a main discharge device connected in series with said load across the source of potential, said main discharge device having an ignitor electrode and a mercury pool cathode, an auxiliary discharge device having an anode, a cathode, and a control electrode, a circuit connecting the cathode of said auxiliary discharge device to said ignitor electrode, an electric storage device interposed between said anode and said source of potential, circuit connected so as to provide a potential pulse in predetermined time relation to said supply potential, and a circuit applying said pulse to said control electrode.

2. In a control system, a source of alternating potential, a load, said load comprising a transformer having a primary winding and a secondary winding, a main discharge device connected in series with said primary winding across said source of potential, said main discharge device having an ignitor electrode and a mercury pool cathode, an auxiliary discharge device having an anode, a cathode, and a control electrode, a circuit connecting the cathode of said auxiliary discharge device to said ignitor electrode, an electric storage device interposed between said anode and said source of potential, a pulse circuit connected so as to provide a potential pulse in predetermined time relation to

said supply potential, and a circuit applying said pulse to said control electrode.

3. In a control system, a source of alternating potential, a load, said load comprising a transformer having a primary winding and a secondary winding, a main discharge device connected in series with said primary winding across said source of potential, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and said source of potential, a pulse circuit connected so as to provide a potential pulse in predetermined time relation to said supply potential, means for adjusting said time relation, and a circuit applying said pulse to said control electrode.

4. In a control system, a source of three phase alternating potential, a load, a main discharge device connected in series with said load across one of said phases, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and another of said phases, a pulse circuit connected so as to provide a potential pulse in predetermined time relation to said three phase potential, and a circuit applying said pulse to said control electrode.

5. In a control system, a source of three phase alternating potential, a load, said load comprising a transformer having a primary winding and a secondary winding, a main discharge device connected in series with the primary winding of said load across one of said phases, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and another of said phases, a pulse circuit connected so as to provide a potential pulse in predetermined time relation to said three phase potential, and a circuit for applying said pulse to said control electrode.

6. In a control system, a source of three phase alternating potential, a load, said load comprising a transformer having a primary winding and a secondary winding, a main discharge device connected in series with the primary load winding of said load across one of said phases, said main discharge device having an ignitor electrode and a mercury pool cathode, an auxiliary discharge device having an anode, a cathode, and a control electrode, a circuit connecting said cathode to said ignitor electrode, an electric storage device interposed between said anode and another of said phases, a pulse circuit connected so as to provide a potential pulse in predetermined time relation to said three phase potential, means for adjusting said time relation, and a circuit applying said pulse to said control electrode.

7. In a control system, a source of three phase alternating potential, a load, said load compris-

ing a transformer having a primary winding and a secondary winding, a main discharge device connected in series with the primary load winding of said load across one of said phases, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and another of said phases, bias means applied to said auxiliary discharge device, said bias being 180 degrees out of phase with said anode potential, a pulse circuit connected so as to provide a potential pulse in predetermined time relation to said supply potential, and a circuit applying said pulse to said control electrode so as to overcome said bias.

8. In a control system, a source of three phase alternating potential, a load, said load comprising a transformer having a primary winding and a secondary winding, a main discharge device connected in series with the primary load winding of said load across one of said phases, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and another of said phases, bias means applied to the auxiliary discharge device, said bias being 180 degrees out of phase with said anode potential, a pulse circuit connected so as to provide a potential pulse in predetermined time relation to said three phase potential, means for adjusting said time relation, and a circuit applying said pulse to said control electrode so as to overcome said bias.

9. In a control system, a source of three phase alternating potential, a load, said load comprising a transformer having a primary winding and a secondary winding, a main discharge device connected in series with the primary load winding of said load across one of said phases, said main discharge device having an ignitor electrode and a mercury pool cathode, an auxiliary discharge device having an anode, a cathode and a control electrode, a circuit connecting the cathode of said auxiliary discharge device to said ignitor electrode, an electric storage device interposed between said anode and another of said phases, bias means applied to said auxiliary discharge device, said bias being 180 degrees out of phase with said anode potential, a pulse circuit connected so as to provide a potential pulse in predetermined time relation to said three phase potential, means for adjusting said time relation, and a circuit including a switch applying said pulse to said control electrode to overcome said bias.
